Primary Examiner — Robert M Spear*Assistant Examiner* — Kendra L Hamilton*(74) Attorney, Agent, or Firm* — Ostrager Chong Flaherty & Broitman PC(57) **CLAIM**

We claim the ornamental design for a lid with loop, as shown and described.

DESCRIPTION

FIG. 1 is a top, front right perspective view of a lid with loop, showing our new design in condition of use;

FIG. 2 is a top, front and right side perspective view of the new design;

FIG. 3 is a top, rear and left side perspective view thereof;

FIG. 4 is a top view thereof;

FIG. 5 is a left side view thereof;

FIG. 6 is a rear side view thereof;

FIG. 7 is a right side elevational view thereof; and,

FIG. 8 is a bottom plan view thereof.

The broken lines and the unshaded surfaces in the Figures depict unclaimed environment.

1 Claim, 5 Drawing Sheets(56)
